UNITED STATES PATENT OFFICE.

HENRY D. SCHALL, OF DETROIT, MICHIGAN, ASSIGNOR TO DETROIT STOVE WORKS, OF DETROIT, MICHIGAN, A CORPORATION OF MICHIGAN.

RANGE.

1,340,986.

Specification of Letters Patent. Patented May 25, 1920.

Application filed April 28, 1919. Serial No. 293,161.

To all whom it may concern:

Be it known that I, HENRY D. SCHALL, a citizen of the United States of America, residing at Detroit, in the county of Wayne 5 and State of Michigan, have invented certain new and useful Improvements in Ranges, of which the following is a specification, reference being had therein to the accompanying drawings.

10 This invention relates to ranges and more particularly to ranges with an elevated shelf or shelves.

In such ranges, it is common practice to extend a stove pipe vertically from the 15 smoke box of the range and through the shelf structure, this being the preferred arrangement when the stove-pipe hole in the kitchen, where the range is to be installed, is in the ceiling or in the upper portion of 20 a wall. In some cases, however, the stove pipe hole in the kitchen may be in the floor thereof or in the lower portion of a wall, and under such conditions it is more convenient to extend the pipe laterally, rear- 25 wardly, or downwardly from the smoke box, eliminating necessity for openings in the shelves.

It is the object of the present invention to secure uniformity of construction by the 30 provision of a range and shelf structure therefor equally well adapted for use with either arrangement of stove-pipe.

In the drawings:

Figure 1 is a perspective view of a range 35 of the elevated shelf type to which the invention is applied;

Fig. 2 is a sectional detail view of one of the shelves showing an opening therein which may accommodate the stove-pipe and 40 a closure for said opening;

Fig. 3 is a similar view showing the closure discarded and a stove-pipe passing through said aperture;

Fig. 4 is a horizontal sectional view of 45 the stove top showing a stove-pipe opening therein and the detachable member which forms a mounting for the stove pipe;

Fig. 5 is a sectional view showing the smoke box provided with a lateral outlet 50 and the detachable member, shown in Fig. 4, applied thereto.

In these views, the reference character 1 designates the top of a range, and 2 a back

plate extending above said top and provided with a shelf structure spaced above 55 the top and comprising the shelves 3 and 4. Said range has its top formed with a stove-pipe opening 4^a and with a depressed seat 4^b marginal to said opening which may receive a cap or closure 4^c when said opening is not used. When the opening is used, a mounting for the stove-pipe base is provided by a collar 4^d engageable with the seat 4^b. Said shelves are respectively provided with openings 5 vertically register- 65 ing with the opening 4^a and respectively adapted for engagement by closures 6. Said openings are proportioned to accommodate a stove-pipe engaging the mounting 4^d, as is indicated in dash lines at 7 in Fig. 1, the 70 closures 6 being discarded when the openings are thus utilized. Said closures when applied to the openings engage seats 8 formed by depressed portions of the shelves marginal to said openings, as is shown in 75 Fig. 2, being secured to said seats by bolts 9 or other suitable fastenings. Thus when the stove-pipe is connected with the smoke box 9^a of the stove at some point other than the opening 4^a, as indicated at 10 in Fig. 80 1, the closures 6 and 4^c seating flush with the top faces of the shelves and top plate 1 present unbroken surfaces and prevent any inconvenience arising from the provision of the openings 5 and 4^c. The same collar 85 4^d may be used to provide a mounting for the stove-pipe when the latter is arranged either as shown at 7 or at 10, said collar being detachably engaged with the range in either 90 position of use by the bolts 11. The opening 12 communicating with the pipe 10 may be formed at various points either in the side or rear wall of the smoke box according to the conditions existing where the 95 range is installed, said opening preferably being made by the workmen installing the range.

The above described invention eliminates necessity of manufacturing two types of ranges, one having provision for extending the stove pipe through the shelves and the other having provision for extending the stove pipe horizontally from the smoke box of the range. Furthermore, since no opening for a horizontal stove pipe is formed in 100 the manufacture of the range, it becomes 105

possible to locate said opening when the same is required most conveniently to satisfy the conditions of each individual installation.

5. What I claim as my invention is:
A stove provided with a plurality of openings for connection with a stove pipe, and

formed with a depressed seat surrounding each opening, and a closure and a stove pipe collar alternatively detachably engageable with said seats.

In testimony whereof I affix my signature.

HENRY D. SCHALL.
